UNITED STATES PATENT OFFICE.

JOSEPH E. WAINWRIGHT, OF BROOKLYN, NEW YORK.

VALVE-LIFTING DEVICE.

Application filed January 7, 1922. Serial No. 527,746.

To all whom it may concern:

Be it known that I, JOSEPH E. WAINWRIGHT, a citizen of the United States, residing at Brooklyn, in the county of Kings 5 and State of New York, have invented certain new and useful Improvements in a Valve-Lifting Device, of which the following is a specification.

The present invention relates to valve 10 spring lifters and has for its principal object to improve upon the structure disclosed in Letters Patent Number 1,392,373 issued to me on October 4, 1921.

A further object of the invention is the 15 production of a simple and efficient device which will facilitate the lifting of a valve spring in order to permit the removal of the retaining pin and the valve spring from engagement with the valve.

Another very important object of the 20 invention is to generally improve upon devices of this nature by providing a tool which will be extremely simple in construction, efficient in operation, capable of being 25 manufactured at a comparatively low cost, and reliable in operation.

With the above and numerous other objects in view as will appear as the description progresses, this invention consists of 30 certain novel features of construction and the combination and arrangement of parts as will be hereinafter fully described and claimed.

In the drawing:—

Figure 1 is a side elevation showing the 35 preferred modification of the tool in an extended or primary position,

Figure 2 is a side elevation of the tool 40 showing the same in a contracted position cooperating with the valve spring seat for lifting the same,

Figure 3 is a fragmentary top plan of the tool,

Figure 4 is an enlarged longitudinal section 45 through the valve engaging end of the tool, on the line 4—4 of Figure 3,

Figure 5 is a longitudinal section through the handle end of the tool,

Figure 6 is a detailed perspective of one 50 of the jaws,

Figure 7 is a similar view showing the jaw inverted,

Figure 8 is a detailed perspective of the handle,

Figure 9 is a detailed section taken substantially on the line 9—9 of Figure 5,

Figure 10 is a longitudinal section through the forward end of the tool showing an auxiliary device attached thereto,

Figure 11 is a detailed perspective of the 60 auxiliary device,

Figure 12 is a longitudinal section through the forward or tool engaging end of a modified form of the invention, and

Figure 13 is a detailed perspective of a 65 modified form of the jaw.

By referring to the drawings it will be seen that 20 indicates the body of the lifter tool generally which is constructed of two lazy-tong frames suitably spaced from each 70 other and operating in substantially parallel planes.

A pair of jaws 21 are carried at the forward ends of the body 20 by being pivotally attached to the ends of the forward link 75 sections 22 while a similar pair of jaws 23 are likewise connected to the adjacent link sections 24. The structure of these jaws 21 and 23 is shown to advantage in Figures 6 and 7 wherein it will be seen that the 80 jaws are curved and milled or provided with notches as at 26 and are provided with rearwardly extending fingers 27 which are likewise milled or notched as at 28 and the rear end is preferably beveled as at 29. 85 An apertured lug is provided at 30 for receiving the rivets 31 which pass through the adjacent link sections 22 or 24. The link sections are held in pivotal engagement with each other and in spaced relation with corresponding link sections on the other frame by the rivets or pins 31 which carry the 90 spacing sleeves 32 which also act as anti-friction rollers for the rearwardly extending fingers 27 of the jaws 21 and 23. A 95 spring washer 33 is associated with each pin or rivet 31 so that when the end 34 is flattened so that the pin or rivet will remain in place there will not be caused a binding action between the link sections. 100

The handle used in conjunction with this tool is shown in detail in Figure 8 and is indicated generally by the numeral 36. This handle consists of a shank 37 being apertured at each end so as to receive at 105 one end a grip bar 38 and at its other end a pin 39 passing through the adjoining ends of the end link sections 40. A bifurcated extension 41 is provided at this end of the shank 37 so as to form a slot 42 the end of 110 which is indicated at 43 and with which the second pin 39' is adapted to abut when

the device is in a contracted position so as to prevent the link sections from abutting each other or over-locking and when in an expanded position the pins designated particularly by the numeral 31' will engage the bifurcations 41 and limit the movement of the link sections.

In Figure 13 I have shown a modification of the jaw wherein the pairs are formed integral with each other having a single rearwardly extending finger 27 and a single apertured lug 30'. The jaws 26' are otherwise similar to the jaws 26 previously described.

15 In Figure 12 a modification has been shown wherein the jaws 21 and 23 are not provided with the milled or notched faces and likewise the fingers 27 are not provided with milled or notched faces. Such a modification is particularly useful on small tools such as would be used with Ford engines and from practical experience I have found that there is no necessity for this milled or notched surface as there is in a larger tool 20 as it will be noted that these milled surfaces or notches engage the rollers on pins 31 and prevent the collapsing of the lazy-tong frames.

In Figures 10 and 11 an auxiliary attachment 30 has been illustrated in conjunction with the tool and as will be evident, this attachment is used where there is considerable space between the two points against which the jaws must bear in order to lift the 35 spring. This auxiliary attachment consists of a jaw 45 which is substantially U-shaped in structure and has a shank 46 extending from its mid portion which is bent in conformity with the structures of the jaws so 40 as to be readily placed and retained in position.

When it is desired to insert the tool for the purpose of lifting the valve spring seat the jaws 21 and 26 are moved to the position 45 shown in Figure 1 and the forward ends of the jaws are forced in between the tappet support and the valve spring seat. The handle 36 is then pushed inwardly to cause the body or lazy tong structure 20 to assume 50 the position shown in Figure 2 thereby raising the valve spring seat to the position shown in Figure 2 and holding the same in this position without further effort on the part of the operator. If it should be found 55 that the space between the tappet support and the valve spring seat is too large then the attachment as shown in Figures 10 and 11 will be used as previously described.

It should be understood that the notches 60 28 upon the fingers 27 will constitute a locking surface for holding the jaws against accidental movement. The spacing sleeves 32 will engage the notches 28 and accomplish this locking function.

65 The projecting fingers of the handle

caused by the bifurcated inner end thereof will engage the spacing sleeves 32 and hold the lazy-tong structures in proper extended position and prevent the same from sagging.

From the foregoing description, taken in connection with the accompanying drawings, it is thought that the operation and construction of my invention will be readily understood without a more detailed explanation. Although I have disclosed my invention with its various modifications with some degree of particularity, it is to be understood that the illustrations of these modifications have been given merely by way of example and I do not consider myself limited to the construction herein disclosed and described other than as hereinafter claimed.

Having thus described my invention what I claim as new is:—

1. A valve spring lifter comprising a body 85 consisting of a pair of lazy-tong frames, valve spring lifting jaws pivotally mounted upon adjacent ends of said frames, and means carried between said lazy-tong frames for limiting the swinging movement of said jaws in one direction and holding said jaws in parallel position when pressure is applied to the valve lifter in the manner and for the purpose specified.

2. A valve spring lifter comprising a body 95 of a lazy-tong structure, valve spring lifting jaws pivotally mounted upon an end of said body, fingers extending from said jaws, said fingers provided with notched surfaces, and means carried by said body for limiting the swing of said jaws in one direction and engaging said notches for preventing collapsing of said lazy tong structure when under pressure in the manner and for the purpose specified.

3. A valve spring lifter comprising a body of a lazy-tong structure, valve spring lifting jaws pivotally mounted upon an end of said body, a handle attached to the other end of said body, and means carried by said handle 110 for preventing the full collapse of said lazy-tong structure either in its extended or contracted positions.

4. A valve spring lifter comprising a body consisting of a pair of parallel lazy-tong structure frames, valve spring lifting jaws pivotally mounted upon one end of said body, an operating handle carried on the other end of said body, and means carried between the lazy-tong frames of said body 115 120 for limiting the swing of said jaws in one direction and holding said jaws in parallel relation when under pressure.

5. A valve spring lifter comprising a body consisting of a pair of lazy-tong structure 125 frames situated in spaced parallelism, valve spring lifting jaws pivotally mounted upon one end of said body, a handle pivotally mounted on the other end of said body, said handle provided with an extension disposed 130

between the lazy tong structure frames for limiting the collapsible movement thereof, and means carried by said body for limiting the swing of said jaws in one direction and 5 holding said jaws in parallel relation when under pressure.

6. A valve spring lifter comprising a body of lazy-tong structure, valve spring lifting jaws pivotally mounted upon an end of said 10 body, means carried by said body for limiting the swing of said jaws in one direction and holding said jaws in parallel relation when under pressure, and an attachment adapted to be associated with said jaws so 15 as to be disposed between one jaw and a bearing surface in the manner and for the purpose specified.

7. A valve spring lifter comprising a pair 20 of separable jaws, means for separating the jaws, and a detachable bearing device associated with one jaw and including a substantially U-shaped body portion having an extension formed on one edge adjacent its mid portion and disposed in substantial 25 parallelism with said edge.

8. A valve spring lifter comprising a body consisting of a pair of lazy-tong frames,

valve spring lifting jaws pivotally mounted adjacent an end of the frame and provided with rearwardly extending portions fitting 30 between the lazy-tong frames and adapted to be held in parallel relation by the lazy-tong frames.

9. A valve spring lifter comprising a body 35 consisting of a lazy-tong frame, lifting jaws carried thereby, a handle for actuating the lazy-tong frame and provided with inwardly extending fingers for engaging the frame and preventing the same from sagging.

10. A valve spring lifter comprising a 40 body consisting of a pair of parallel lazy-tong frames, lifting jaws interposed therebetween, a handle carried near the opposite ends of the frames and interposed therebetween, the handle being provided with inwardly projecting fingers for engaging the frames and preventing the same from sagging while in an extended position.

In testimony whereof I affix my signature in presence of two witnesses.

JOSEPH E. WAINWRIGHT.
